DESIGN FOR A CRADLE TOY

Eoina Nudelman, Chicago, Ill.

Application August 12, 1944, Serial No. 114,856

Term of patent 7 years

(Cl. D34—15)

To all whom it may concern:

Be it known that I, Eoina Nudelman, a citizen of France, residing at Chicago, in the county of Cook and State of Illinois, have invented a new, original, and ornamental Design for Cradle Toys, of which the following is a specification, reference being had to the accompanying drawing, forming part thereof.

Fig. 1 is a front elevation of a cradle toy, showing my new design;

Fig. 2 is a left-hand end view; and

Fig. 3 is a section on the line 3—3 of Fig. 1.

I claim:

The ornamental design for a cradle toy, as shown.

EOINA NUDELMAN.
